UNITED STATES PATENT OFFICE.

LYMAN WIGHT AND ORISON G. EWINGS, OF WHITEWATER, WISCONSIN.

IMPROVEMENT IN GRAIN-DRILLS.

Specification forming part of Letters Patent No. 122,299, dated December 26, 1871.

To all whom it may concern:

Be it known that we, LYMAN WIGHT and ORISON G. EWINGS, both of Whitewater, in the county of Walworth and State of Wisconsin, have invented a new and useful Broadcast Seeder, Grain-Drill, Corn-Planter, and Corn-Cultivator combined; and we do hereby declare the following to be a full, clear, and exact description of the same, reference being had to the accompanying drawing forming part of this specification, in which—

Figure 1, Sheet 1, is a top-plan view, part of the hopper being broke away to show the feeding device. Fig. 2, Sheet 1, is an end elevation, one of the traction wheels being removed. Fig. 3, Sheet 1, is a perspective view of the feeding device detached from the hopper. Fig. 4, Sheet 2, is a front elevation of the machine. Fig. 5, Sheet 2, is an end elevation of the machine adapted for broadcast seeding, one of the traction-wheels being removed. Fig. 6, Sheet 2, is a perspective view of the seed-scatterer detached from the machine. Fig. 7, Sheet 2, is a detached sectional view of the corn-hopper, and Fig. 8, Sheet 2, is a bottom-plan view of the corn-feeding plate and its operating pinion detached from the hopper.

Similar letters of reference in the accompanying drawing indicate the same parts.

Our invention has for its object to combine in one machine a broadcast seeder and cultivator, a grain-drill, a corn-planter, and a corn-cultivator, for the purpose of saving the expense attending the construction of these machines separately. To this end the invention consists in the combination itself, and in the parts that necessarily relate thereto. While we do not intend in this application to cover distinct improvements in all of the machines, our purpose is to claim such improvements as interchangeably effect the operation of the individual machine. Our invention, therefore, further consists in the method of regulating the quantity of seed sown to the acre either broadcast or in drills. It further consists in the construction of the seed-scatterers and conveyers, which are so attached to the hopper as to yield when brought in contact with obstructions, and which are also adapted for removal from the hopper when the machine is to be used as a corn-cultivator. The conveyers, however, are used both for broadcast seeding and drilling. It consists further in the method of throwing the

feeding devices in and out of gear with the driving-wheels. It further consists in the means employed for communicating motion from the driving-wheels to the corn-dropper, and for throwing the same in and out of operation, which latter movements are effected by the same devices which are employed for raising the drag-teeth from the ground in the broadcast seeders and for throwing the feeders in and out of gear in both the broadcast seeder and drill. It further consists in the construction of the frame to adapt it for the reception of the corn-planter, the corn-cultivator, the drill-tubes, scatterers, and conveyers, and the drag-teeth of the broadcast seeder. It further consists in the adaptation of the drill-tubes for the reception of seed from the hopper of the broadcast seeder or corn from the corn-hopper. The relation of these various parts to each other is such that the grain-hopper delivers the seed for both broadcast sowing and drilling; the corn-hopper is supported by the grain-hopper, while both hoppers deliver the different kinds of grain into the same tubes.

In the accompanying drawing, A is the hopper of the broadcast seeder and drill, having axles cast upon or affixed to its ends for the reception of the wheels B C of the machine. The ends of the hopper are cast with grooves or flanges upon their proximate faces for the reception of the vertical front board, and the inclined bottom and rear boards, the various parts being clamped together by the longitudinal bolt D, the partitions E, and the transverse bolts F. G is the tongue of the machine, secured to the front of the hopper by the angle-iron H and strengthened by the brace-rods I. J is a beam passing under the tongue, and supported by brackets K from the front of the hopper, on a line with or a little below its bottom. L are brace-rods, which further connect the beam to the tongue and afford additional lateral support for the latter. The beam J carries at its rear side a rod, M, from which the drag-bars N and drill-tubes are supported, and to which the lifting-bar P in rear of the hopper is attached by rods or bars Q. The device for feeding the grain from the hopper consists in an inverted serrated cup, R, attached to a vertical crank-shaft in such a manner as to enter the discharge openings in the bottom of the hopper, fitting such opening with easy contact. The feeder is hung loosely in a bracket, S, which bracket

is slotted to fit over a stud projecting from the front board of the hopper. Upon the end of the stud, between the bracket and feeder, is pivoted a toothed cam, T, which engages with a spur, u, affixed to the bracket upon the under surface of its upper arm. The quantity of seed fed to the acre, both in broadcast seeding and in drilling, is determined by the position of the serrated cup R with respect to the feed openings in the hopper, and this position is regulated by the toothed cam in the following manner: When the feed is to be changed to increase the quantity per acre, for example, the bracket is raised, sliding freely upon the stud of the cam. This, of course, lifts the cup R and increases the size of the discharge openings formed by the serrations in said cup. The cam T is then turned to the left and engages with the spur U, whereby the bracket is held in position and the cam prevented from slipping. To decrease the quantity of seed fed from the hopper the cam is turned to the right, permitting the bracket to descend, as will be readily understood. The face of the cam is provided with graduations corresponding to the number of notches and extending from left to right, so that it may be easily and accurately set to feed the requisite quantity of grain per acre.

The feeders are operated in the following manner. W is a pinion mounted upon a vertical shaft, which has its bearings in a bracket, X, pivoted to the end of the hopper. This pinion engages with a toothed rim, Y, affixed to the inner face of the left-hand driving-wheel, and is provided upon its upper surface with a crank-wheel, Z, connected to the crank-shaft of one of the feeders by a rod, A¹, passing through the end of the seed-box. Inasmuch as the left-hand feeder is too near the end of the seed-box to allow the proper movement of the rod A¹, the latter is connected to the crank-shaft of the second feeder, as shown in Fig. 1, the several crank-shafts being connected by rods B'. By this arrangement of mechanism an oscillating movement is imparted simultaneously to all the feed-cups when the driving-wheel of the machine is rotated.

C¹ C¹ are brackets, projecting from the rear board of the hopper to afford bearings for the rock-shaft D¹ and for the grooved pulleys E¹, which are hung in their outer faces so as to rotate in a direction parallel to the hopper. F¹ is a lever pivoted to the center of the rock-shaft, and connected to chains G¹ upon each side of the pivot, which chains, passing through the ends of the brackets and over the pulleys E¹, are attached to the lifting-bar P. H¹ is a spring-arm, secured to the pivoted bracket X upon the end of the seed-box, and together with such bracket forms a spring-lever the rear end of which is connected to the lever F¹ by the rod I¹.

This combination of devices secures the following results: When the lever F¹ is thrown to the right, as shown in Fig. 1, the lifting-bar P is lowered to permit the operation of the drag-teeth J¹. This movement of the lever carries the end of the spring-arm H¹ to the right and engages the pinion W with the toothed rim Y. The

object in employing the spring-arm H¹ in connection with the pivoted bracket is threefold: First, the connection of the pinion W with the crank-shafts of the feeders is such that any extended movement of the pivoted bracket X would materially retard the oscillation of the feeders. Secondly, the space between the end of the hopper and the toothed rim Y is so small that the bracket is permitted but a limited movement, no more, in fact, than is necessary to allow the teeth of the pinion to clear those of the rim Y. Thirdly, the elasticity of the spring holds the pinion and toothed rim in contact with a yielding pressure, and thereby prevents any unusual strain upon the teeth of either.

If, on the contrary, the spring-arm should be replaced by a rigid bar extending to the rear the distance requisite to form the connection with the lever F¹, the movements of the latter would be restricted to such an extent as to preclude the possibility of lifting the drag-teeth, and would so increase the throw of the bracket X to and from the toothed rim as to bind the pinion when engaged therewith, and displace the feeders when disengaged. The elasticity of the arm H¹, therefore, permits the requisite throw of the pinion, and after this has reached its limit allows the further movement of the lever F¹ to raise the lifting-bar.

By moving the lever F¹ to the left it raises the lifting and drag bars and throws the pinion out of gear with the toothed rim to stop the operation of the feeders. The lever is held to the right and left, respectively, by hooks K¹ affixed to the brackets C¹, as shown in Fig. 1. The rock-shaft D¹ permits the lever to be turned up or down so that it shall be within reach of the operator when walking or when riding upon the hopper. L¹ are the scattering-tubes, having open backs, and extending from the under side of the hopper between the two beams of each drag-tooth. Each tube is provided within its enlarged lower end with three diamond-shaped pins, m', arranged as shown, for the purpose of scattering the seed as it falls upon them. The tubes are formed with enlarged upper ends, which are pivoted at the rear side to ears n', projecting from the bottom of the hopper upon opposite sides of the feed openings. O¹ is a spring-yoke, having its ends bent outward in opposite directions to form the pivots for the scatterers, which pivots are held in place by the tension of the spring. By compressing the two arms of the yoke the pivots are withdrawn from the ears and the scatterers readily detached. By this attachment the scatterers swing backward to pass over an obstruction, their own gravity causing them to drop into the proper position for receiving the seed after the obstacle is passed.

P¹ are the drill tubes, which, when the machine is employed for drilling grain, are attached to the drag-bar rod M, occupying the places of the drag-bars N, which are in this case removed. The bifurcated arms Q¹, by which the drill-tubes are attached to the rod M, are pivoted to the under side of said tubes a short distance from the upper ends thereof. The inclination of the drill-tubes

is adjusted by means of pins r' in the arms Q^1 and the perforated segments S^1 , which project downward through said arms from the upper ends of the tubes. The conveyers from the hopper to the drill-tubes are the same in form as the scatterers, with the exception of the lower ends, which are reduced in size to enter the ends of the drill-tubes, and are, of course, not provided with scattering-pins. The lower ends of the drill-tubes are formed with colters T^1 , the rear ends of which are divided to open the ground for the reception of the seed. Over each colter, at the rear of the tubes, is arranged a scraper, U^1 , by which the seed is covered; and this scraper is made adjustable by means of a set-screw, V^1 , to regulate the depth at which the seed is sown. The drill-tubes are each attached to the under side of the lifting-bar P , and by it are raised and lowered, as necessity requires, the feeders being thrown in and out of operation to correspond with the position of the tubes.

Thus it will be seen that the same mechanism which is employed to raise and lower the drag-bars and throw the feeders in and out of gear with the driving-wheel is utilized to raise and lower the drill-tubes and adjust the devices by which they are fed.

The mechanism for dropping corn is located upon the frame and hopper, thus far described, and is designed for planting simultaneously two rows of corn in drills, employing for this purpose two of the drill-tubes P^1 , as we will now proceed to describe.

W^1 is the corn-hopper, made in the form of a cylindrical box, having a close-fitting cover, and is supported upon the front of the hopper A by means of legs $X^1 Y^1$, the former entering a socket, Z^1 , affixed to the front of said hopper A , and the latter stepped in sockets formed in the beam J , each side of the tongue. A^2 is a hollow cone, having its base formed with or united to an annular plate, B^2 , whose outer edge projects from the cone in the form of a flange, and is provided with a circle of close perforations. This perforated flange C^2 constitutes the seed-plate, and rests upon the bottom of the corn-hopper. The inner edge of the annular flange, projecting within the base of the cone, is formed with cogs, which engage a pinion, D^2 , mounted upon a shaft, e^2 , which has its bearings in the bottom of the hopper.

Motion is communicated to the seed-plate through the pinion D^2 in the following manner: The hub of the driving-wheel C is grooved upon its inner end or provided with a grooved pulley, from which a belt or chain, F^2 , extends to a grooved pulley, G^2 , mounted upon the front end of a lever, H^2 , which, in its turn, is pivoted to the end of the seed-box A . By means of a belt or chain, I^2 , the pulley G^2 transmits its motion, received from the driving-wheel, to a grooved pulley, J^2 , affixed to the lower end of the pinion-shaft e^2 . By this arrangement of devices the operation of the driving-wheel causes the rotation of the seed-plate within the corn-hopper. When the latter is filled with corn and the machine set in motion the corn drops through the seed-plate, and from

thence through the bottom of the hopper at two opposite points, k^2 , entering bent tubes L^2 , and by them is conducted to the right and left to enter the drill-tubes in continuous streams. When the corn-planter is to be used the drag-teeth and their bars are removed, together with all of the drill-tubes with the exception of two, one at each end of the hopper A , as shown in Fig. 4. If desired the bent tubes L^2 may be made of flexible material or of metal, and attached to the corn-hopper by a flexible connection. The bar L^3 , pivoted to the apex of the cone, rests upon the perforated seed-plate for the purpose of feeding the corn properly through the perforations. The belt lever H^2 , in front of its pivot, rests upon a spring, M^2 , attached to the end of the hopper for the purpose of holding up the pulley G^2 to preserve the proper tension of the belt F^2 . N^2 is a rod hung upon the rear end of the spring-lever, and extending downward through one end of the lifting-bar P . This rod forms a guide for the lifting-bar and a support for the adjustable collar O^2 , so that when said bar is lifted it shall bear against the collar to lift the outer end of the lever H^2 against the tension of its spring, thereby depressing the pulley G^2 , slackening the belt F^2 , and throwing the corn-planter out of operation.

By this arrangement the same frame that supports the drill and broadcast seeder also supports the corn-planter, the hopper of both seeder and drill supplying a further support, while the drill-tubes of the latter are utilized as the means by which the corn is drilled into the ground and covered.

A still further combination exists between the corn-planter and the machines hereinbefore described in the mechanism by which the corn-planter is thrown in and out of operation—that is to say, the mechanism by which the latter result is accomplished also raises and lowers the drill-tubes of the grain-drill, the drag-bar of the broadcast seeder, and throws the feeders of both the drill and seeder in and out of gear.

The last feature of our invention consists in the corn-cultivator, which is used in connection with the drag-teeth of the broadcast seeder. P^2 are the cultivator-teeth, whose arms Q^2 extend vertically upon each side of the tongue, passing through the ends of a plate, R^2 , affixed to the upper surface of the latter. The arms are connected together below the beam by a perforated plate, S^2 , and to the under side of the tongue by the rods T^2 , which may consist of separate pieces, or of one rod bent into the form shown so as to form an eye adapted to articulate upon the hook U^2 projecting from the under surface of the tongue. The rods T^2 are made vertically adjustable upon the cultivator-arms by perforations in the latter, which receive pins passed through the ends of the rods. V^2 are right-angular foot-levers, pivoted at their angles to the front of the beam J so that their upper ends shall extend nearly to the tongue, to be operated by the feet of the driver. Their lower ends are perforated and connected to the perforated plate S^2 by means of rods W^2 .

By this arrangement the driver, seated upon the seed-box, moves both cultivator-teeth to the right

and left by pressing alternately upon the right and left foot-lever.

By raising the plate S^2 upon the cultivator-arms and lowering the ends of the connecting-rods upon the foot-levers a simultaneous pressure upon the foot-levers forces the cultivator-teeth into the ground, and by lowering the plate S^2 and raising the outer ends of the connecting-rods the same pressure upon the foot-levers lifts the cultivator-teeth out of the ground, so that by either arrangement the cultivator-teeth are completely under the control of the operator.

The cultivator is designed to straddle the row of plants to be cultivated, and is used in connection with the drag-teeth of the broadcast-seeder, four of the latter working upon each side of the row of plants and the central ones being either turned up or removed, as most convenient. The cultivator-teeth are provided with sockets X^2 to receive the arms P^2 , which are held therein by set-screws Y^2 . By this connection the teeth may be turned and adjusted upon their arms to throw the dirt to or from the plants.

The cultivator is held out of operation by the notched yoke Z^2 , which straddles the tongue and is pivoted thereto, so that when the cultivator is raised the plate S^2 catches upon the notches and is thereby held suspended out of contact with the ground. By moving the upper end of the yoke toward the seed-box the plate S^2 is released and the cultivator falls to the ground by its own gravity. The draft is applied to the combined machines by a clevis, Z^3 , affixed to the under side of the tongue, as shown clearly in Fig. 2.

Having thus described our invention, what we claim as new therein, and desire to secure by Letters Patent, is—

1. The combination, with one common frame, of the broadcast-seeder and cultivator, a grain-drill, a corn-planter, and a corn-cultivator, substantially as herein shown and described, for the purpose specified.

2. In combination with the crank-pinion W the pivoted bracket X and the spring-arm H^1 , we claim the lever F^1 and connecting-rod I^1 , substantially as described, for the purpose specified.

3. The open-backed tube L^1 , constructed with an inclosed head, and with its widened mouth provided with the diamond-shaped pins, arranged as described, said tube being hinged to the under side of the hopper, substantially as herein shown and described.

4. The spring-pivot yoke O^1 in combination with the tube L^1 and the ears n' of the hopper, substantially as described, for the purpose specified.

5. The corn-planter, supported by the frame of the machine and the hopper of the seeder and drill, and adapted for operation from one of the driving-wheels of the seeder and drill, substantially as described, for the purpose specified.

6. The corn-planter adapted for use in connection with two of the tubes of the drill by means of the bent tubes L^2 for the purpose of planting one or two rows of corn in drills, substantially as herein shown and described.

7. The corn-cultivator, mounted upon the frame of the seeder, drill, and corn-planter, and adapted for operation in connection with the drag-teeth, substantially as described, for the purpose specified.

8. The broadcast-seeder, the grain-drill, the corn-planter, and the drag-teeth, all adapted to be thrown in and out of operation by the movements of one common lever and lifting-bar and their intermediate connections, substantially as herein shown and described.

9. The seed-plate of the corn-hopper, operated from one of the driving-wheels of the drill and seeder by means of the pinion P^2 and grooved pulley J^2 upon the shaft e^2 , the belts $F^2 I^2$, grooved pulleys G^2 , and a grooved pulley upon the hub of the wheel, substantially as herein shown and described.
